UNITED STATES PATENT OFFICE.

JULIUS G. BREITENSTEIN, OF CHICAGO, ILLINOIS, ASSIGNOR TO INDEPENDENT BUTTON AND MACHINE COMPANY, OF CHICAGO, ILLINOIS, A CORPORATION OF ILLINOIS.

PRESS FOR BUTTON-MAKING AND LIKE PURPOSES.

No. 899,098.

Specification of Letters Patent.

Patented Sept. 22, 1908.

Application filed April 8, 1907. Serial No. 367,003.

To all whom it may concern:

- Be it known that I, JULIUS G. BREITENSTEIN, a citizen of the United States, residing at Chicago, in the county of Cook and State of Illinois, have invented new and useful Improvements in Presses for Button-Making and Like Purposes, of which the following is a specification, reference being had to the drawings forming a part thereof.
- 19 This invention relates to the class of machines which are commonly in the form of a press having dies which coöperate by movement toward and from each other in successive processes or steps of a process such as 15 are required in making buttons composed of a plurality of elements which are assembled and clenched together in the processes performed by the dies.

The purpose of the invention is to provide 20 improved means for causing one of the dies which has a yielding member to act as if such member were unyielding when coöperating with one of two opposed dies with which it is alternately brought into coöperation, while 25 permitting it to act by the yielding of its yielding member while in coöperation with the other of the two opposed dies.

The invention consists of the features of 30 construction illustrated and described, as indicated in the claims.

In the drawings:—Figure 1 is a side elevation of this improved machine. Fig. 2 is a section at the line 2—2 on Fig. 1, showing the upper die which has the yielding member 35 in position for coöperating with the lower die with which it is designed to coöperate without the yielding of said member. Fig. 3 is a view similar to Fig. 2 showing, in line for co-operation with the upper die, the die on the 40 carrier which requires the yielding member of the upper die to yield in properly performing the process. Fig. 4 is a section at the line 4—4 on Fig. 3. Fig. 5 is a view similar to Fig. 2 showing the lower carrier 45 adapted to rotate instead of oscillate. Fig. 6 is a similar view showing the rotating die-carrier at a position at which no die is in line with the upper die. Fig. 7 is a view similar to Fig. 2 showing the device which is interposed between the upper die members for locking it mounted on the standard instead of on the lower die carrier. Fig. 8 is a detail side elevation, partly sectional, showing the locking device of the form shown in Fig. 7,

section being made axially through the 55 lower portion of said device.

The structure shown in the drawings comprises a standard, A, having mounted in its upper part a vertically reciprocating head, B, normally upheld by a spring, C, and 60 thrust downward for coöperation of the dies by a cam lever, D, whose action will be obvious from its form as shown in Fig. 1. The upper die carried in the reciprocating head, B, comprises a fixed member, E, and a 65 yielding member, E'. Mounted upon the bed is an oscillating carrier, F, having its fulcrum at f for swinging horizontally through an arc whose chord is the distance between the centers of the two dies, G and 70 H, carried by said oscillating carrier and by its oscillation brought alternately into line with the upper die. Any suitable stops, as the pins, J, on the bed encountered by the oscillating carrier, limit its oscillation with- 75 in the range above stated, stopping it at the opposite limits with the dies upon it accurately alined, each in turn, with the upper die, as above described. On the fixed mem- 80 ber, E, of the upper die, there is a flange, E", which is conveniently formed by a nut which serves as a means of securing the die to the reciprocating head, B, (this double use of the nut being, however, merely inci- 85 dential) such flange being in position over- hanging the yielding member, E', of the die and constituting a stop limiting the upward yielding movement of said member. The interval between the flange and said yielding member when the latter is at its lower position corresponds to the range of yielding movement required. On the oscillating carrier, F, there is mounted a vertically re- 90 ciprocating element, K. This element is conveniently a hollow rock-shaft or sleeve 95 mounted for reciprocation on the stud or bearing shaft, L, which projects up rigidly from the oscillating carrier, a spring, M, be- 100 ing coiled about the stud, L, reacting between the latter and the sleeve, or rock-shaft, K, to yieldingly uphold the latter which is stopped by a nut, l, on the upper end of the rigid shaft, L. Preferably the sleeve, K, has freedom for a short range of oscillation about the shaft, L, and the spring, M, has its up- 105 per end, M', engaged with the sleeve in the slot, k, of the latter, and being engaged at its lower end in the standard as well as

stopped thereagainst and coiled so as to have elastic reaction circularly about its axis, its engagement at the upper end with the sleeve as described causing it to yieldingly hold the sleeve at the position shown in Fig. 3, at which it is stopped by the encounter of the short stud, K^1 , on the sleeve against the abutment, f' , on the carrier. Near the upper end of the sleeve, K , it has a horizontally projecting arm or finger, K^1 , which is at proper position for passing between the flange, E^{10} , and the yielding member, E^1 , of the upper die when the carrier swings to position for alining the lower die, G , with said upper die, as seen in Fig. 2. In moving to this position the arm, K , encounters laterally the interior element of the head, B , between the yielding member, E^1 , and the flange, E^{10} , and yields slightly as the die comes into position to accommodate the diameter of said interior element, be it greater or less; and the purpose of mounting the element, K , so that it can thus yield about its axis is to adapt the device to coöperating accurately and properly with dies of different sizes in which the diameter of the center element may be greater or less. The width vertically of the arm, K^1 , is such as to so far occupy the interval between the member, E^1 , and the flange, E^{10} , as to prevent or limit the sliding movement of the member, E^1 , on the interior element of the die to whatever extent such movement is required to be limited for the proper action of the die. If a slight movement is to be permitted, the arm, K^1 , will be slightly narrower vertically than the interval between the member, E^1 , and the flange, E^{10} , as shown. It will be seen that when the die, H , is alined with the upper die, the arm, K^1 , being entirely out of the way of the two coöperating dies, the member, E^1 , of the upper die will yield upon its encounter with the lower die, but when the die, G , is alined with the upper die, such yielding will be prevented to the extent determined by the vertical width of the arm, K^1 , and that as said upper die descends to coöperate with the lower die, G , the sleeve, K , will be carried down with it, sliding on the said shaft, L , and being restored by the spring, M , as the die rises.

It will be obvious that the expedient shown for locking the upper die may be employed with a lower die-carrier adapted to rotate as well as with one adapted to oscillate as in the figures above described. Such rotating die-carrier is shown in conjunction with the locking device in Figs. 5 and 6, the die-carrier, F^x , having two pairs of dies, G^x and H^x , the carrier having adjacent to each of the dies, G^x , the locking device, K , with all its accessory parts of identically the construction shown in Figs. 1, 2, 3 and 4. It will be seen that as the carrier is rotated, the locking arm, K^1 , having been carried into

locking position in relation to the upper die at one step of the rotating movement will be carried out of such position, yielding freely for rotation about its axial support, L , in order to pass away from the upper die and out of locking relation thereto. A spring catch, N , engages a notch, f^x , on the rotating carrier at each position at which the carrier is halted for registration of one of its dies with the upper die, four of such notches, f^x , being therefore provided when the carrier has four dies as shown.

Instead of mounting the locking device upon the rotating or oscillating carrier, it may be mounted on the standard, as shown in Figs. 7 and 8. Such construction in connection with an oscillating die is shown in Patent No. 836,916, granted to me November 27, 1906. In Figs. 7 and 8 of this application, the same device is shown in connection with the rotating carrier. In this form the locking device comprises a hollow rock shaft or sleeve, K^y , mounted for rotation and also for reciprocation upon the vertical shaft or stud, L^y , which is mounted in the standard, as seen in Fig. 8, the spring, M , being provided precisely as in the form shown in the other figures (Fig. 4) for engaging the slot, R , in the hollow rock shaft or sleeve, K^y , and being stopped endwise against said device for yieldingly resisting its descent and returning it to elevated position. In this form, the lower dies on the rotating carrier with which the locking device is not designed to be engaged have a laterally offset stop finger, P , in position to encounter the arm, K^z , of the locking device and swing said device aside to position shown in dotted line in Fig. 7 when the dies having this offset stop finger come to alinement with the upper die. To prevent the stop device from being retracted too far about its axis by the spring, M , when out of engagement with either die, there is provided a short heel piece or tail, K^w , corresponding substantially to the lower arm, K^z , of the device shown in Figs. 1, 3 and 4 which stops against the upright shank of the standard, A , as seen in Figs. 7 and 8.

I claim:

1. In a machine for the purpose stated, in combination with a standard, a reciprocating die having a yielding member; a carrier mounted on the standard for movement transverse to said reciprocating movement; a plurality of dies mounted on such carrier; an arm extending transversely to the direction of said reciprocation mounted on the carrier for movement therewith and also for movement in the direction of said reciprocation, adapted to be carried between and out from between the yielding and unyielding members of the upper die by said transverse movement of the carrier.
2. In a machine for the purpose stated, in combination with a standard, a reciprocating

die having a yielding and an unyielding member; a die-carrier mounted for movement transverse to that of the reciprocating die; a plurality of dies mounted on such carrier in position to be brought into line one by one with the reciprocating die for coöperation therewith; an element on the carrier mounted for reciprocation parallel with the reciprocating die, and means for holding it 10 yieldingly at one limit of its path of reciprocation, said element having an arm adapted when the element is at said limit to be carried between the yielding and unyielding members of the reciprocating die by the transverse movement of the carrier and also to be withdrawn by transverse movement from said interposed position.

3. In a machine for the purpose stated, in combination with a standard, a reciprocating die having a yielding and an unyielding member; a die carrier mounted for movement transverse to that of the reciprocating die; a plurality of dies mounted on such carrier in position to be brought into line one by 20 one with the reciprocating die for coöperation therewith; a rock shaft on the carrier mounted for reciprocation parallel to the reciprocating die and also for oscillation in transverse direction; a spring which yieldingly holds said rock shaft at one limit of its path of reciprocation and at one limit of its range of oscillation, said rock shaft having an arm adapted when said rock shaft is at said limit to be carried between the yielding and unyielding members of the reciprocating die by the transverse movement of the carrier and to be withdrawn from such interposed position by transverse movement.

4. In a die press, the combination with a reciprocating die having fixed and yielding members, of a carrier having a plurality of

dies thereon and movable to bring either of its dies opposite the first-mentioned die, and a yielding arm pivotally mounted on the carrier and arranged to swing between said fixed and yielding members in one direction and to clear the same in the other direction. 45

5. In a die press, the combination with a reciprocating die having fixed and yielding members, of a carrier having a plurality of dies thereon and movable to bring either of its dies opposite the first-mentioned die, a rod projecting from the carrier, and a swinging arm yieldingly mounted on the rod and projecting in position to strike the reciprocating die between said fixed and yielding members when moved in one direction and to clear the same when moved in the other direction. 50

6. In a die press, the combination with a reciprocating die having fixed and yielding members, of a carrier having a plurality of dies thereon and movable to bring either of its dies opposite the first-mentioned die, a pivot rod projecting from the carrier, a transverse swinging arm having a bearing sleeve mounted to turn and to slide on the rod and projecting in position to engage the reciprocating die between said fixed and yielding members when moved in one direction and 60 to clear the same when moved in the other direction, a spring mounted on the rod and yieldingly supporting said bearing in both sliding and turning movement, and a stop on the rod, to limit the swing of the arm. 65

In testimony whereof, I have hereunto set my hand at Chicago, Illinois, this 4th day of April, A. D., 1907.

JULIUS G. BREITENSTEIN.
